UNITED STATES PATENT OFFICE.

GILLES HOLST AND EKKO OOSTERHUIS, OF EINDHOVEN, NETHERLANDS, ASSIGNEES
TO NAAMLOOZE VENNOOTSCHAP PHILIPS' GLOEILAMPENFABRIEKEN, OF EINDHOVEN, NETHERLANDS, A LIMITED LIABILITY COMPANY OF NETHERLANDS.

RECTIFIER FOR ALTERNATING CURRENTS.

1,410,062.

Specification of Letters Patent. Patented Mar. 21, 1922.

Application filed May 10, 1920. Serial No. 380,238.

To all whom it may concern:

Be it known that we, GILLES HOLST and EKKO OOSTERHUIS, subjects of the Queen of the Netherlands, residing at Eindhoven, in the Province of North Brabant, in the Kingdom of the Netherlands, have invented certain new and useful Improvements in or Relating to Rectifiers for Alternating Currents, of which the following is a specification.

For rectifying alternating currents, discharging tubes can be used in which one of the electrodes is brought to a high temperature and it then acts as a cathode. Generally the said cathode is constructed as an incandescent filament, whilst the anode or anodes are usually constructed in the form of a sheet or a rod.

This invention relates to an apparatus of this type in which however, the electrodes are so constructed that they can be used successively either as incandescent cathodes or as anodes, whilst an electrode, which is no longer fit for use as a cathode, can then be used as an anode.

This construction has the advantage, that the life of the apparatus is considerably increased. In case the incandescent filament is burnt out, one of the other electrodes is used for this purpose, whilst the defective incandescent filament can be used as an anode.

The invention is illustrated in the accompanying drawing.

The drawing shows a rectifier for three-phase current. The rectifier consists of a

discharging tube (1) in which four spirals (2) of tungsten or other suitable material are used. One of the spirals is brought to incandescence. The three others are used as anodes. If the first spiral is burnt out, one of the others can act as the cathode and this can be repeated until none of the four spirals is any longer fit for use.

What we claim is:

1. A discharging tube rectifier for alternating currents, having a plurality of electrodes, each comprising a conductor for an electric current, whereby it may be rendered incandescent so as to serve as a cathode, while another of said electrodes serves as an anode, and each of said electrodes being adapted, when burned out, to serve as an anode, while another of said electrodes serves as a cathode.

2. A discharging tube rectifier for alternating currents, having a plurality of electrodes, each comprising a conductor for an electric current, whereby it may be rendered incandescent so as to serve as a cathode, while other of said electrodes serve as anodes, and each of said electrodes being adapted, when burned out, to serve as an anode, while another of said electrodes serves as a cathode.

In testimony whereof we have affixed our signatures in the presence of two witnesses.

GILLES HOLST.

EKKO OOSTERHUIS.
